DENTAL INCISAL PACKING TOOL

Robert Philip Berger, 17110 Clemons Drive,
Encino, Calif. 91316

Filed Dec. 29, 1969, Ser. No. 20,652

Term of patent 14 years

Int. Cl. D24—02

U.S. Cl. D24—1 D

FIG. 1 is a perspective view of a dental incisal packing tool, showing my new design.

FIG. 2 is a side perspective view of the said dental incisal packing tool;

FIG. 3 is a top perspective view of the said dental incisal packing tool;

FIG. 4 is an end perspective view of the said dental incisal packing tool; and

FIG. 5 is an enlarged view of a portion of the grasping surface for said dental incisal packing tool.

I claim:

The ornamental design of a dental incisal packing tool, substantially as shown.
